(57) **CLAIM**

The ornamental design for a light cover, as shown and described.

DESCRIPTION

FIG. 1 is a perspective view of an embodiment of a light cover;

FIG. 2 is a front elevational view of the light cover;

FIG. 3 is a rear elevational view of the light cover;

FIG. 4 is a right side elevational view of the light cover;

FIG. 5 is a left side elevational view of the light cover;

FIG. 6 is a top plan view of the light cover; and,

FIG. 7 is a bottom plan view of the light cover.

The broken lines shown in the FIGURES illustrating a light and portions of the light cover are included for the purpose of illustrating environmental elements only and form no part of the claimed design.

1 Claim, 5 Drawing Sheets
